UNITED STATES PATENT OFFICE.

JOHN W. DISSETTE, OF CHICAGO, ILLINOIS, ASSIGNOR TO WARD'S PRODUCTS CO., INC.,
OF CHICAGO, ILLINOIS.

DESIGN FOR A BOTTLE.

Application filed October 28, 1926. Serial No. 19,508. Term of patent 14 years.

To all whom it may concern:

Be it known that I, JOHN W. DISSETTE, a citizen of the United States, residing at Chicago, Illinois, have invented a new, original, and ornamental Design for a Bottle, of which the following is a specification, reference being had to the accompanying drawing, forming part thereof.

I claim:

The ornamental design for a bottle as shown.

JOHN W. DISSETTE.
